UNITED STATES PATENT OFFICE

161,003

COMBINATION CIGARETTE DISPENSER AND ASH TRAY

Myron H. Colman, Chicago, Ill.

Application November 26, 1949, Serial No. 6,275

Term of patent 3½ years

(Cl. D85—2)

To all whom it may concern:

Be it known that I, Myron H. Colman, a citizen of the United States, and resident of Chicago, in the county of Cook and State of Illinois, have invented a new, original, and ornamental Design for a Combination Cigarette Dispenser and Ash Tray, of which the following is a specification, reference being had to the accompanying drawings, forming a part thereof:

Fig. 1 is a top plan view of a combination cigarette dispenser and ash tray, embodying my new design;

Fig. 2 is a side elevational view of the same; and

Fig. 3 is a sectional view taken on the line 3—3 in Fig. 1 of the drawings and viewed in the direction indicated.

I claim:

The ornamental design for a combination cigarette dispenser and ash tray, substantially as shown.

MYRON H. COLMAN.
